UNITED STATES PATENT OFFICE.

CHARLES H. RITZMAN, OF DUMONT, IOWA.

POOL-GAME-TALLYING DEVICE.

Application filed May 17, 1920. Serial No. 381,989.

To all whom it may concern:

Be it known that I, CHARLES H. RITZMAN, a citizen of the United States of America, and a resident of Dumont, Butler County, 5 Iowa, have invented certain new and useful Improvements in Pool-Game-Tallying Devices, of which the following is a specification.

My invention relates to improvements in 10 pool-game tallying devices, and the object of my improvement is to supply for the use and convenience of proprietors of pool-halls and others, a registering device adapted for tallying games played, serially, and which 15 is operable to return to a zero position.

This object has been accomplished by the 20 means which are hereinafter described and claimed, and which are illustrated in the accompanying drawings, in which Fig. 1 is a front elevation of the discoidal face of the device only; Fig. 2 is a rear elevation of the rear face of the device, with parts broken away; Fig. 3 is a rear elevation of the device, with parts removed or broken away, 25 and showing the manually operable means for returning the mechanism to zero position; Fig. 4 is an elevation of certain supporting and operating elements of the device as removed therefrom, and Fig. 5 is a 30 perspective detail view of the operating mechanism, with parts removed or broken away, showing in full lines the positions of the pawls at the instant when they are all disengaged from the ratchet-wheels, the dotted lines showing the usual position of the pawl 34.

In said drawings, similar numerals of reference denote corresponding parts throughout the several views.

40 The numeral 1 denotes a disk having at the top an escutcheon 2 provided with an opening through which is displayed any numeral 4 of a series of numerals arranged around one face of another disk 3, the latter 45 mounted rotatably to the rear of said disk 1, within a rearwardly directed marginal flange 8 of the disk 1. The disk 1 is suspended fixedly by means of a tubular element 6, whose lower end is fixed in a hollow 50 casting 5 secured to the top of the disk, and whose upper end is secured in a hollow hanger 9 fixed above, as on a ceiling above a pool table.

The numeral 21 denotes a short axis or 55 shaft projecting rearwardly from the center of the rear face of the disk 1, the disk

3 being centrally orificed to permit it to be rotatably mounted on said shaft immediately to the rear of the disk 1. Upon the rear face of the disk 3 is fixedly secured coaxially a ratchet-wheel 18, part of whose circumferential periphery at 17 is denuded of teeth, the opposite edges of the bounding teeth being slopingly curved as shown.

The rear face of said ratchet-wheel is 60 raised to furnish a coaxial ratchet-wheel 19, whose teeth face rearwardly. From the latter ratchet-wheel projects radially a fixed 65 detent 23. The raised central part of said combined ratchets is provided with a coaxial hollow thus providing a hollow spring-seat 20 closed at the rear. A spiral spring 22 is mounted in the hollow of this spring-seat, with one end connected to the inner wall 70 of the spring-seat, and its inner end connected to said shaft 21, whereby the spring is reactively wound up when the disk 3 and said ratchets are together rotated in one direction.

A plate 26 is centrally orificed to be seated 80 removably on the shaft or axis 21 over said combined ratchets, and serves as a fixed support for certain pawls adapted to movably engage teeth of the ratchet 18 and a projection 23 on the ratchet 19 respectively. 85 An operating element in the form of a bar 27 medially orificed is mounted on said shaft 21 over the shield or plate 26 to rock back and forth, and its arms are approximately 90 of equal length, each orificed at the extremity. In one of the orificed extremities is hung a hooked hanger 37, and in the other orificed extremity is hung a chain 38, the lower end of the chain having a ring-connection with one angle of a triangle 39 used 95 to spot the balls on the table beneath.

In the plate 26 is an arcuate opening 28 immediately over the ratchet-teeth 19. On the outer face of the arm of said bar 27 which carries said triangle is fastened an 100 elastic bar 30 whose free end or tip 35 is bent toward the ratchet 19, traversing the opening 29 in said arm to movably engage the teeth of said ratchet. A plate-spring 31 is mounted on said pawl to reinforce it resiliently.

The numeral 24 denotes a bar crossing the disk 3 diametrically vertically, with medial orifice seating it on the shaft 21 over said plate 26 and rock-bar 27, the upper end of 110 which is removably secured to the casting 5, and the lower end to a small plate 7 fixed on

the disk rim 8. A longitudinally channelled plate 25 is mounted over the upper part of the vertical bar 24.

The numeral 32 denotes a pawl pivoted at one end to the overlying plate 26 with its 5 detent 34 held for occasional engagement with the detent 23 by a helical spring 22 connected between it and the bar 24, and this pawl is extended to provide an arcuate arm 10 for operation in actuating the pawl. On the front face of the plate 26 is a detent 36 adapted to act as a stop for the detent 23 when the disk 3 has arrived at either end of 15 opposite rotations.

15 A triangular plate 14 is pivoted at 15 to the upper part of the front face of the plate 26 and has at one angle a pin 16 which serves as a pawl or dog in movably engaging the teeth on the ratchet-wheel 18, and has at 20 another angle a ring-connection with one end of a coiled spring whose opposite end is secured to the bar 24. A connecting-rod 13 is connected between the third or uppermost angle of said plate and the lower end 25 of a cord 12. The cord 12 is passed through the hollow of the tubular hanger 6 and the casting 9, thence through a screw-eye fixed in the ceiling over the station of the proprietor, and is furnished with a terminal ring 11.

30 The triangle 39 may be hung on the hooked hanger 37 when not in use. When the triangle is used to spot the balls, its chain 38 swings down the connected arm of the rock-bar 27, and the pawl 35 rotates the 35 ratchet-wheel through the length of one tooth of the ratchet-face 19. This advances serially a number 4 on the disk 3, the number being visible through the opening of the escutcheon 2 of the front disk 1. This successive actuation in rotating the disk 3 in 40 a step-by-step movement, winds up the spiral spring 22, but the guard-pawl 16 locks the teeth of the ratchet 19 against retrograde movement. The uppermost pawl 16

45 during this operation meshes with roots of teeth of the ratchet 18 to prevent a retrograde rotation of the disk due to the re-action of the spring 22, but the lowermost pawl 34 is idle or disengaged, as it lies in the 50 path of movement of the detent 23, and is intended to only engage said detent at the end of a rotation. That is, the detent 23 during the last step of a rotation engages the pawl 34 and presses it out of its path 55 yieldingly and resiliently while the driving-pawl 35 is rotating the ratchet 18 through the last tooth thereof of the counting series, the pawl 34 then snapping back of and engaging the rear edge of the detent 23 just 60 as the detent engages and is stopped by the stationary pin or detent 36. During this last movement of the ratchet 18, the uppermost pawl 16 is disengaged from teeth of 65 said ratchet because of the passage thereunder of the toothless rim part 17 of the

ratchet. The position of the pawl 34 and its arm 32 at this time is indicated by the dotted lines in Fig. 5.

The extremity of the arm 32 is provided with a cross-bar which lies in the path of the lever 27 while descending. As the whole series of games has now been played and indicated on the dial, the device is reset as follows. The triangle 39 may be hung on the hanger 37, whose weight rocks downwardly the adjacent end of the lever, so that the opposite end of the lever rocks upwardly, causing the spring-pawl 35 to ride out of the slot 28 and upon the rear face of the fixed plate 26, thus holding the pawl 35 disengaged from the ratchet 18. Simultaneously, the lever 27 engages the cross-bar on the extremity of the arm 32 and rocks the latter outwardly to disengage the pawl 34 from the detent 23. Fig. 5 shows the positions 80 of said movable elements at this moment while the ratchet 18 is released from all of the pawls 16, 35 and 34, at which time the reaction of the coiled spring 22 rotates the ratchet 18 rearwardly to its zero position 85 ready for another series of actuations, the detent 23 then engaging the opposite side of the fixed detent 36 to stop its rotation beyond said zero position. Attention is invited to the fact that the encasing of the 90 throw-off rod 13 and cord 12 in the hanger-tube 6 prevents unauthorized meddling by a 95 player with them.

In case players desire to quit playing before the completion of a series of games, 100 the cashier may reset the device from a distance by pulling the cord 12, which lifts the pawl 16 out of mesh with teeth of the ratchet 18, and as the triangle 39 has been placed on the hanger 37 at the end of the 105 last game played, the pawls 34 and 35 are disengaged, so that the released ratchet is free to be returned by the spring 22 to zero position.

Having described my invention, what I 110 claim as new, and desire to secure by Letters Patent, is:

1. In a device of the character described, a fixed shaft, a dial rotatably mounted thereon, a spring connected between said dial and shaft to exercise tension upon the dial when rotated in one direction, inner and outer ratchets having oppositely directed teeth fixed concentrically upon said dial, the outer ratchet having a portion of its circuit 115 denuded of teeth, a resiliently controlled pawl yieldingly engaging teeth of said outer ratchet, a single detent extending radially outwardly from the said outer ratchet, a fixed stop-member extending into the path 120 of rotation of said detent to stop the rotation of said ratchet at either limit of opposite rotations thereof, a rock-lever medially pivoted on said fixed shaft, a pool-game triangle flexibly suspended on one arm 125 130

of said lever, a hanger suspended on the opposite end of said lever, a resiliently-controlled pawl mounted on the said lever and engaging teeth on the inner ratchet, a fixed plate positioned between said ratchets and said lever, and adapted to have the last-mentioned pawl ride upon it and be disengaged from said ratchet when said lever is rocked to its limit in one direction, and 5 a resiliently-controlled pawl positioned yieldingly in the path of rotation of said detent and having an arm positioned in the path of movement of the opposite end of said lever, the latter when moved in one 10 direction pushing over said arm to withdraw 15

the last-mentioned pawl from the path of movement of said detent.

2. A housing, a tubular support fixed to and communicating with said housing, and depending from an elevated ceiling, a registering device in said housing provided with a ratchet-wheel, a pawl cooperating with said wheel, an actuating element for said pawl extending within said tubular member, and emerging therefrom at its upper end 20 near the ceiling, and arranged for operation from a distant point.

Signed at Waterloo, Iowa, this 3rd day of May, 1920.

CHARLES H. RITZMAN.
